UNITED STATES PATENT OFFICE.

ARTHUR A. LAZIER, OF BUFFALO, NEW YORK.

TIMING DEVICE FOR INTERNAL-COMBUSTION ENGINES.

Application filed July 19, 1920. Serial No. 397,206.

To all whom it may concern:

Be it known that I, ARTHUR A. LAZIER, a citizen of the United States, residing at Buffalo, in the county of Erie and State of New York, have invented new and useful Improvements in Timing Devices for Internal-Combustion Engines, of which the following is a specification.

This invention relates to a timing device for controlling the injection of fuel in Diesel and semi-Diesel engines or any other type of engine where a change in the timing of the valve mechanism is required or desirable.

15 In engines of this character, as heretofore constructed, the fuel is injected into the working ends of the cylinders at fixed or invariable intervals with the result that the fuel is admitted too early for starting, 20 causing the engines to pound and in many cases racking them to such an extent as to render them wholly unserviceable.

It is the principal object of this invention to provide a timing device which permits of readily varying the time of fuel injection in starting, or when running at high speeds, with a view of overcoming such objections.

A further object is to provide a device 30 of this character which is simple in construction, reliable in operation and applicable to existing engines without materially altering their construction.

A still further object is the provision of 35 an indicator which co-operates with the timing device to show the degree at which the fuel is being injected.

In the accompanying drawings: Figure 1 is a vertical section of an ordinary type 40 of Diesel engine equipped with the timing device. Figure 2 is a sectional view of the usual fuel pump and actuating cam controlled by the device. Figure 3 is a vertical section on line 3—3, Fig. 1. Figure 4 is a fragmentary bottom plan view of 45 the gearing for transmitting motion from the crank shaft to the cam shaft.

Similar characters of reference indicate 50 corresponding parts throughout the several views.

My improved timing device is shown in connection with a two-cycle semi-Diesel explosion engine, but it is to be understood that the same is applicable to a four-cycle 55 engine of a similar type, as well as other internal combustion engines.

Referring to Fig. 1 of the drawings, 10 represents the upright cylinder of the engine opening at its lower end into the crank case 11, the latter being air tight with the exception of the usual air inlet controlled by the inwardly-opening valve 12. 13 indicates the piston and 14 the crank shaft with which it is operatively connected by the usual rod 15. The cylinder communicates at one side with the crank case by the air inlet port 16, while opposite said port is the usual exhaust port 17 which communicates with the exhaust pipe of the engine, not shown, these ports being covered and uncovered by the piston in a manner common to such engines.

18 represents the cylinder head in the upper end of which is mounted the usual hot bulb 19 which carries the spray nozzle 20 of ordinary construction, fuel being admitted to this nozzle at a predetermined point in the cycle of operations of the engine. The fuel is fed to the spray nozzle by a pipe 21 through which it is forced by a pump 22 which may be of any suitable and well known construction. As shown in Fig. 2 of the drawings, this pump comprises a vertically reciprocating plunger 23 operating in a cylinder 24. As the plunger rises in the cylinder fuel is drawn from the fuel tank, not shown, through the suction valve 25 and on the downstroke of the plunger, the fuel is forced past the outlet valve 26 and delivered to the spray nozzle 20. The reciprocating movement of the plunger 23 is effected by a cam 27 fixedly mounted on a cam shaft 28 journaled in a housing 29 arranged adjacent the crank case 11. Motion is transmitted from the crank shaft 14 to the cam shaft 28 by any suitable means, but preferably by a worm or spiral gear 31 on the crank shaft which meshes with a spiral gear 32 on the cam shaft. The devices for varying the angular position of the cam, to effect a variation in the stroke of the pump plunger and thereby retard or accelerate the time at which fuel is injected into the cylinder of the engine, are preferably constructed as follows:

The worm 31 is splined or slidably connected to the crank shaft by a key 33, so that it may be shifted lengthwise thereon to effect a partial rotation of the cam shaft 110 and an angular adjustment of the cam, this adjusting function of the worm being ad-

ditional to its function of transmitting continuous rotary motion to the cam shaft during the operation of the engine.

34 indicates a shifting fork or yoke engaging an annular groove 35 in the outer portion of the worm 31 and carrying a nut 36 which engages a horizontal adjusting screw 37 arranged parallel with the crank shaft. This screw is journaled in the upper portion of the housing 29 and held against longitudinal movement by a shoulder 38 and a collar 39 which abut against the inner and outer bearings of the screw, respectively. The unthreaded outer end of this screw extends through the outer wall of said housing and has fixed thereto a hand wheel 40 for turning it.

To enable the operator to know the exact number of degrees of angular movement imparted to the cam 27 upon rotating the hand wheel 40 in either direction, a suitable indicating device is provided which is located for convenient observation by the operator. This indicating device may be of any suitable construction, but as shown in Figs. 1 and 3 of the drawings, it preferably comprises a pointer 41 carried by the nut 36 and traversing a scale 42. This pointer projects through a slot 43 in the top of the housing 29 and the scale 42 is arranged on an upright plate 44 rising from one side of the slot. This scale indicates in degrees the angular position of the cam and the time at which the fuel is injected into the working end of the cylinder in a given adjustment of the cam.

In the use of this timing device, if the operator, after starting the engine, finds that the same is pounding, he knows that the fuel valve is opening too early. He thereupon rotates the hand wheel 40 in a clockwise direction to effect the proper rotation of the cam shaft 28 to cause the angle of lead of the fuel injection cam 27 to be retarded and consequently effect a later injection of the fuel. The number of degrees of angular movement of the cam will appear on the indicator scale, the "0" on the scale indicating the normal rated setting of the cam and corresponding to the position of the cam just prior to actuating the fuel-pump plunger, with the piston in its highest position, as shown in Figs. 1 and 2. Any angular movement of the cam from this position will move the pointer correspondingly and show the number of degrees on the indicator scale. As the speed of the engine gradually increases and attains its normal running speed under load, the operator gradually rotates the hand wheel in a counter-clockwise position, until the engine runs smoothly. On the other hand, if it is found that the fuel is being injected too late, as would be evidenced by the failure of the engine to pull its rated load, the hand wheel is rotated

in a counter-clockwise direction to cause the angle of lead of the fuel injection cam to be advanced and consequently effect an earlier injection of the fuel.

This improved timing device, while comparatively simple in construction, is easy to operate and permits a nice regulation or variation of the time of fuel injection according to the engine speed and load pulled, thereby effecting the greatest economy in operation and making it possible to secure late ignition under light load. This last mentioned advantage permits of running the engine at slow speeds and makes it unnecessary to shut down as would be necessary in engines having a fixed or uniformly timed fuel injection.

Furthermore, this timing device is equally applicable to the starting cam for regulating the air injection when starting the engine. It also lends itself to application on reversible engines of this type without the use of additional cams or other mechanism.

I claim as my invention:

1. In a timing device for internal combustion engines, the combination of means for injecting fuel into the engine, a crank shaft, a cam shaft carrying a cam for actuating said fuel injection means, transmission members on said shafts, respectively, for imparting motion from the crank shaft to the cam shaft, the transmission member on said crank shaft being slidable lengthwise thereof to rotate said other transmission member and change the angular position of said cam, and means for shifting said slidable transmission member.

2. In a timing device for internal combustion engines, the combination of means for injecting fuel into the engine, a crank shaft, a cam shaft carrying a cam for actuating said fuel injection means, and gear-elements on said shafts, respectively, for transmitting motion from the crank shaft to the cam shaft, the gear-element mounted on the crank shaft being slidable lengthwise thereof to rotate said other gear-element and the cam shaft, whereby the angular movement of said cam is varied to advance or retard the actuation of said fuel injection means.

3. In a timing device for internal combustion engines, the combination of means for injecting fuel into the engine, a crank shaft, a cam shaft having a cam for actuating said fuel injection means, spiral gears for transmitting motion from the crank shaft to the cam shaft, said crank-shaft gear being shiftable lengthwise of the crank-shaft to rotate the cam shaft and vary the angular movement of said cam, and means for shifting said crank-shaft gear.

4. In a timing device for internal combustion engines, the combination of means for injecting fuel into the engine, a crank shaft, a cam shaft having a cam fixed there-

on for actuating said fuel injection means, a spiral gear splined to said crank shaft to slide thereon, a spiral gear fixed on said cam shaft and meshing with said first-named

5 gear, a shifting yoke engaging with the latter, and means for actuating said yoke to shift said crank shaft gear in either direction on said shaft.

5. In a timing device for internal combustion engines, the combination of means 10 for injecting fuel into the engine, a crank shaft, a cam shaft having a cam fixed thereon for actuating said fuel injection means, a spiral gear splined to said crank shaft 15 to slide thereon, a spiral gear fixed on said cam shaft and meshing with said first-named gear, a shifting yoke engaging with the latter, and a screw operatively connected with said yoke for shifting said crank-shaft 20 gear on said shaft.

6. In a timing device for internal combustion engines, the combination of means 25 for injecting fuel into the engine, a crank shaft, a cam-shaft having a cam fixed thereon for actuating said fuel injection means, a spiral gear splined to said crank shaft to slide thereon, a spiral gear fixed on said cam shaft and meshing with said first-named gear, a rotatable screw arranged parallel 30 with said crank shaft and held from longi-

tudinal movement relatively thereto, a yoke threaded on said screw and engaging said crank-shaft gear, and means for operating said screw.

7. In a timing device for internal combustion engines, the combination of means for 35 injecting fuel into the engine, a crank shaft, a cam shaft having a cam fixed thereon for actuating said fuel injection means, a housing for said cam shaft, a spiral gear splined 40 on said crank shaft, a spiral gear fixed on said cam shaft and meshing with said first-named gear, a rotatable screw journaled in said housing and held from longitudinal movement relatively thereto, a yoke threaded 45 on said screw and engaging said crank shaft gear, and means for rotating said screw.

8. In a timing device for internal combustion engines, the combination of means for 50 injecting fuel into the engine, a crank shaft, a cam shaft having a cam for actuating said fuel injection means, a spiral gear splined on said crank shaft, a spiral gear fixed on said cam shaft and meshing with said first-named gear, a shifting yoke engaging the 55 latter, means for actuating said yoke, an indicator-scale, and a pointer movable with said yoke and traversing said scale.

ARTHUR A. LAZIER.
